UNITED STATES PATENT OFFICE.

PAUL E. COLLINS, OF LYNN, MASSACHUSETTS.

BOAT-PROPELLED MECHANISM.

SPECIFICATION forming part of Letters Patent No. 398,703, dated February 26, 1889.

Application filed April 26, 1884. Renewed August 16, 1886. Serial No. 211,070. (No model.)

To all whom it may concern:

Be it known that I, PAUL E. COLLINS, of Lynn, in the county of Essex and Commonwealth of Massachusetts, have invented certain new and useful Improvements in Boat-Propelling Mechanism, of which the following, taken in connection with the accompanying drawings, is a specification.

This invention relates to boat-propelling mechanism; and it consists in the devices and combinations of devices hereinafter fully set forth and particularly claimed.

In the accompanying drawings, Figure 1 is a perspective view of a section of a boat, a paddle-wheel and its feathering-paddles, the mechanism for regulating the movements of the paddles, the mechanism for propelling the wheels, and fully illustrates the general manner in which the said several parts are organized and combined together. Fig. 2 is a plan of a section of the parts shown in Fig. 1, the section being made on line *x x*. Figs. 3 and 4 are side views of certain detached parts of the mechanism made on an enlarged scale, 25 and to be more fully described hereinafter.

The boat represented in the accompanying drawings has a very narrow body, being after the style of the ordinary velocipede-boat; but the invention is applicable to other boats and 30 is not limited to any particular style. The invention will, however, be first described as combined with a boat of the peculiar style represented in the drawings.

The body *B*, as before remarked, is quite 35 narrow, and is provided with outriggers *C C*, also a frame-work, *D D*, adapted to support the seat *E*, on which the person riding is supposed to sit. The feet of the rider are to be placed on the pedals *a a*, and thereby may be 40 revolved the crank-shaft *f* and the wheel *b*, from which motion is transmitted through belt *c* and wheel *d* to revolve the wheel-shaft *F*, and thus propel the boat. Said wheel-shaft *F* carries a paddle-wheel on each end, 45 and the shaft has its bearings in the outriggers *C*. The wheel-shaft *F* is also provided on either end with an air-tight chamber, located by preference just outside of the paddle-wheels, which, being always filled with air, 50 prevent the boat from tipping over sidewise.

In order to prevent the paddle-wheels from lifting by reason of their own natural buoy-

ancy or by reason of the air-chambers, a spiral spring (not shown) is placed in the box *C*, with one end bearing upward against the box and 55 the opposite end bearing down on the shaft. This spring needs, of course, to be only strong enough to overcome the buoyancy of the wheels and air-chambers.

By reference to Fig. 1 it will be observed 60 that the paddles *2 2 2*, &c., have their tangs arranged to turn in suitable bearings or grooves in the plate *3*, while their outer ends are connected by the band *4*. Each paddle is constructed with more area on one than on 65 the other side of the line intersecting its pivoted points, and the side with the larger area being allowed to enter the water first the action of the water will effect a half-turn of the paddle, allowing it to come out of the water 70 edgewise. Paddles adapted to operate in this manner are not new; but the combination of such paddles with the plate *3* has not, to my knowledge, ever been used prior to my invention thereof. The objects of such a plate are 75 to avoid the lifting of water incident to and necessarily done by the arms of the ordinary feathering-wheels. The power expended in such manner is always a pure loss, and though it amounts to little when the wheel is partly 80 submerged, yet it amounts to much when the wheel is run low down in the water, and, as it is desirable to extend the wheel as far down as possible in order to secure the advantage of denser water, I prefer and find it a gain of 85 power to construct the wheel with central plate, *3*, as described.

All feathering-wheels heretofore constructed are dependent upon the action of the water to turn the paddles—*i. e.*, the paddles enter 90 the water nearly edgewise, the wider side of the blade being ahead, and the water bearing against this causes the paddle to turn round, bringing the wider side of the paddle in the rear and allowing the paddles to come out of 95 the water edgewise. It is very desirable that the paddle should not turn before it begins to lift out of the water; but the moment that the paddle enters the water it is subjected to the action thereof, and it not unfrequently 100 happens that the paddle completes its half-turn before it gets far into the water—that is, before it completes its downward movement. This is more commonly the case when-

ever the wheel is made to revolve rapidly whenever it is far into the water. In this way much power is lost, as the paddle fails to take hold of the water at the very moment when its work would be the most effective in driving the boat. To obviate this difficulty I have provided a locking mechanism adapted to engage and hold the paddle till it reaches the desired point for work, and then releases the same to permit the quarter-turn, and then firmly holds it again until it passes the working-point, and again releases it as it commences to lift water, and allows it to further turn and come out of the water edgewise.

15 The several parts which together compose the locking and releasing mechanism are fully represented in Fig. 3 of the drawings, and the manner of combining this mechanism with the boat is clearly represented in Fig. 2. It 20 will be observed that the arm 10 has its rear end attached firmly to the boat at or nearly in line with the wheel-shaft F, and extends horizontally outward till its branches 11, 12, 13, and 14 come nearly in contact with the 25 center plate, 3, of the paddle-wheel.

It is essential that the end faces of the arms or extensions 12 13 14 should be in the same vertical plane and parallel to the plate 3, while in the end of the lever 15 (see Figs. 1 30 and 3) is a sliding stud, 16. This stud bears its inner end against the incline and face of arm 11, and by an obvious operation of the lever 15 this stud 16 may be carried toward or away from the said plate 3. It is necessary to have only a very slight movement of the stud 16 in this direction, and it should be adapted to come slightly nearer to the plate 3 than the extensions 12 13 14 are allowed to come—that is, the distance between the 40 stud 16 extended and the plate 3 should be slightly less than the distance between plate 3 and the end surfaces of arms 12 13 14, and a proper movement of lever 15 should bring the stud back into the same 45 plane with the end surface of said arms 12 13 14. These several extensions are intended to trip the pawl 17, which is pivoted on the wheel-plate 3 and is carried round by the same. One of these pawls is provided for 50 each paddle in the wheel, and on the tang or shaft of the paddle is arranged a small wheel, 18, provided on its periphery with notches, and the pawl 17, by dropping into one of these notches, holds the wheel, and thus locks and 55 holds the paddle from turning farther until released by the pawl coming in contact with some one of the extensions 11 12 13 14. We now suppose the whole to be revolving in the direction indicated by the arrow 20, Fig. 1, 60 and the paddle in position to enter the water edgewise, the side having the larger area being foremost. The paddle entering the water thus is held and prevented from turning until the wheel has moved sufficiently far round 65 to bring the pawl 17, which holds the paddle, into contact with the end of stud 16, whereby the pawl is lifted out of the notch in the wheel

18, and the paddle is turned by the action of the water till the pawl 17 drops into the next notch in the wheel 18. This brings the paddle at right angles to the body of the boat and into the proper position for work. It is desirable that the paddle should attain this position as quickly as possible after it reaches the point for effective work, and the arm 11 70 should be located accordingly, and to further hasten the operation of the paddle, as well as to insure its turning in the right direction, the edge of the paddle should be slightly beveled. The paddle should remain in the position stated until it passes to that part on the opposite side of the wheel where work cannot effectually be performed on account of the lifting of water, and at this point the pawl 17 will have been carried sufficiently far 75 round to engage with the end of the arm 12, whereby the pawl in passing is again lifted and the paddle is allowed to make a further quarter-turn to come out of the water edgewise. It is now desired to bring the paddle into position for again entering the water, which requires a further half-turn. This half-turn is 80 effected by means of the cam 21. To this end the cam 21 is secured to the side of the wheel 18, as represented in Fig. 3, and is in line to 85 strike the end surface of arm 14 whenever it is carried by the wheel-plate 3 round to that point, and at the moment the cam 21 engages the end of the arm 14 the pawl 17 is lifted by the arm 13, thereby allowing the cam to roll 90 in passing the end of arm 14, and thus effect a half-turn of the wheel 18, and with it of course the paddle-blade, thus bringing the paddle into position to re-enter the water, as 95 above described.

100 It will of course be understood that in some cases it might be desired to turn the wheels without operating the paddles—that is, allowing the paddles to pass through the water edgewise. To provide for this, I arrange the wheel 18 eccentrically in reference to the shaft of the paddle in such manner that three of the notches in the periphery of the wheel 18 will 105 be equidistant from the shaft of the paddle, and the distance between the shaft of the paddle and either of these three notches will be 110 slightly less than the distance from said shaft to the other or fourth notch. The paddle, the wheel 18, and the pawl 17 are also arranged 115 relatively to each other so that when the paddle is in position for entering the water, as 120 above described, the pawl 17 will be located in that notch of the wheel 18 which is farthest from the paddle-shaft. While in this notch the rear end of the pawl lies closer down to 125 the plate 3 and escapes the ends of the several arms 12 13 14, and therefore it is only necessary to move back the stud 16, (which may be 130 done by a suitable movement of the lever 15, as above described,) and the pawl will pass entirely round without being lifted, and when it is desired to have the paddles operate again the stud 16 must be pushed forward sufficiently to engage and lift the pawl out of this 135

particular notch. It then falls into the other notches, where it will be lifted by the other arms, 12 13. The cam 21 carries on one end a small wheel, 22. Said wheel is mounted 5 upon a curved arm, 24, as fully illustrated on an enlarged scale in Fig. 4 of the drawings. The manner of combining this with the cam 21 is better shown in Fig. 3. The purpose of this wheel is, in part, to avoid the friction at 10 the point where the cam is about to leave the arm 14, and for this purpose it is allowed to turn in one direction, being prevented from turning in the opposite direction by means of the pawl and ratchet shown in Fig. 4. This 15 wheel, whenever the paddle-wheel is revolved in the direction opposite to that indicated by the arrow 20, and described above, comes first into contact with the end arm, 14, and yields downward slightly, the arm 24 being for this 20 purpose adapted to spring slightly downward, and in this manner the straining and possible breaking of parts is avoided, that might otherwise occur while the pawl 17 is coming into engagement with the arm 13, to be lifted thereby, and allow the paddle to be reversed 25 into position for entering the water, and the paddle in passing the arms 12 11 will be operated, as before described.

I claim—

30 1. The combination, with a boat, of the outriggers forming a bearing for the shaft F, the paddle-wheels consisting of air-tight chambers and outer rings, the paddles having bearings in the plate 3 and the said ring, and 35 means, substantially as described, for operating said wheels to propel the boat, substantially as described.

2. The combination, with the boat, of the paddle-wheels consisting of air-tight chamber 40 and ring, movable feathering-paddles between said chamber and ring, and means, substantially as described, under the control of the operator adapted to engage said paddles and hold the same during a part revolution of the 45 wheel, and means, as described, to automatically release the same, substantially as set forth.

3. The combination of a wheel having movable feathering-paddles, substantially as de-

scribed, the wheel 18, connected to the shaft 50 of the paddle and notched as described, the pawl 17, pivoted to the plate 3, one end thereof engaging with the notches of the wheel 18, and means, substantially as described, adapted to engage the passage end of said pawl intermittently and lift the same to release the wheel 18, substantially as described. 55

4. In a boat of the class described, the arm 10, connected to the boat and extending horizontally outward, having a branch, 11, and the lever 15, having the stud 16, combined with the wheel 18 and pawl 17, whereby in the revolution of the paddle-wheel the said pawl 17, holding the paddle-blade, comes in contact with the stud 16, thereby acting upon the wheel 18 to turn the paddle, substantially as described. 60

5. The combination, in a boat of the class described, of the shaft carrying the paddle-wheels, the air-tight chambers having face- 70 plate 3, and the ring 4, of larger diameter than the plate 3 and in line therewith, the said plate and ring forming bearings for feathering paddle-blades having their movement between the plate 3 and ring 4, substantially as described. 75

6. In a boat of the class described, having the arm 10 connected thereto, with branch arms 12, 13, and 14, the combination of the wheel 18, pawl 17, and cam 21, carried by the 80 plate 3, whereby when the said cam 21 strikes the arm 14 the said pawl 17 is lifted by the arm 13, thus allowing the cam to roll in passing the end of the arm 14 and effecting the half-turn of the paddle-blade. 85

7. The combination, in a boat of the class described, with the arm 10, having the branch 14, of the plate 3, carrying the wheel 18, pawl 17, and cam 21, with its spring-arm 24 and wheel 22, whereby the friction is avoided in the 90 movement of the cam 21 over the arm 14 and straining prevented by the action of the spring-arm 24, substantially as described.

PAUL E. COLLINS.
